VAPORIZER

Application filed March 24, 1925. Serial No. 17,937.

This invention aims to improve the operation of internal combustion engines and more particularly to adapt such engines to operation with heavy liquid fuel not easily volatilized, such as kerosene, petroleum distillate and fuel oil for example. The invention further aims to enable such fuels to be utilized in operating internal combustion engines primarily designed for running on gaso-line, to simplify the construction of heavy fuel vaporizers and to adapt one for vaporizing either light or heavy fuels.

Further aims and advantages of the invention appear hereinafter in connection with the description of the illustrative embodiment thereof shown in the drawings, wherein

Fig. 1 is a side elevation of a vaporizer adapted for use with a multi-cylinder vertical engine;

Fig. 2 is an end elevation and Fig. 3 is a top plan view, of the vaporizer shown in Figs. 1 and 2;

Fig. 4 is a horizontal cross-section of the same, the section being taken on the line 4—4 in Fig. 1;

Figs. 5 and 6 are vertical cross-sections on the lines 5—5 and 6—6, respectively, in Figs. 2 and 3, looking in the direction of the arrows numbered to correspond;

Fig. 7 is a vertical cross-section on the line 7—7 in Figs. 1 and 3, looking in the direction of the arrows;

Fig. 8 is a view similar to Fig. 7 showing a modified form of the invention; and

Fig. 9 is a cross-section thereof on the line 9—9 in Fig. 8, looking in the direction of the arrows.

In Figs. 1 to 5, inclusive, the parts are shown in their normal running positions, and in Fig. 6 they are shown in their positions for starting the vaporizer into action.

The embodiment of the invention illustrated in Figures 1 to 7 comprises a body or casing 10 of suitable construction for supporting the various operating parts, and which is provided with a fuel well or supply chamber 11 and a flanged outlet pipe 12 (see Fig. 2) for conducting the vaporized fuel to the inlet pipe of the engine and which may form a support for the vaporizer. A throttle

valve 13 (see Fig. 7) may be fitted in the outlet pipe 12 for controlling the supply of fuel mixture to the engine in the usual manner.

The main fuel nozzle or jet 14 (see Figs. 5 and 7) is arranged in the throat 15 at the upper end of the tube 16, and an adjustable needle valve 17 is arranged above the nozzle to regulate the amount of liquid fuel delivered by the nozzle. The lower end of the mixing tube 16 has an auxiliary air inlet 18 closed by an automatic air valve 19 which is opened by the suction of the motor. A spring pressed pin 20 limits and controls the amount of opening of this valve 19. The tension of the valve pin spring may be adjusted to suit the conditions of use of the vaporizer by turning the housing cap 21, which is threaded on to the spring housing 22, and which in turn is likewise adjustable to vary the point at which the pin 20 will be engaged by the valve 19. Lock nuts 23 hold the cap and housing in adjusted position. This auxiliary air valve should be adjusted to suit the amount of opening of the main fuel nozzle 14 for ordinary running conditions at normal engine speeds. When starting the valve 19 may be held closed by means of a bell crank lever 24 having suitable means for controlling it from a convenient point.

For high speeds and full load conditions an auxiliary fuel nozzle 25 is provided (see Fig. 5) which discharges into the mixing chamber 26 above the throat 15. The nozzle 25 is normally closed by a valve 27 held on its seat by a spring 28 but which may be lifted by a lever 29 controlled by the high speed air valve 30. This valve 30 is normally held up to close the opening from the outer air into the mixing chamber by an adjustable spring 31. The spring 31 rests on a block 32 in the adjustable spring housing 33. The lower end of the valve stem slides through the block 32, and the upper end projects above the valve and has its extremity screw threaded to receive adjustable lock nuts 34 which actuate the lever 29 when the valve 30 is opened. The spring 31 is adjusted to hold the valve 30 closed except when the suction on the vaporizer is strong, due to a wide throttle opening, as at high speeds. A locking screw 35 actu-

ated by a lever 36 connected to any suitable operating means is provided for holding the valve closed when starting the vaporizer.

Liquid fuel is supplied to the auxiliary fuel nozzle 25 through a duct 37 from the fuel well which passes alongside of the vaporizer tube 16 between it and the combustion and heat transfer chamber 38, hereinafter described (see Figs. 5 and 7) for the purpose of heating and vaporizing the fuel prior to its issuance from the nozzle 25. The nozzle 25 is set at a level above that of the fuel in the supply chamber 11 to avoid feeding an undue amount of fuel.

The combustion and heat transfer chamber 38 (see Fig. 6) is supplied with a rich combustible fuel mixture through the mixing tube 39 in which a fuel jet nozzle 40 is located. The amount of orifice opening of the nozzle 40 is controlled by means of the needle valve 41 which is adjusted by the screw 42. The jet nozzle 40 is connected to the fuel well 11 by a suitable duct 43. Sufficient air for combustion of a portion of the fuel is admitted to the mixing tube 39 through the port 45 under normal running conditions.

For starting operation of the vaporizer, air is admitted through the electric heater chamber 46, where it is heated, to the fuelizer mixing tube 39 and past the nozzle 40. An electric resistance element 47, preferably a carbon electrode, is arranged in a suitable insulated holder 48 in the chamber 46, and is connected to a storage battery or other source of electric energy by means of the conductor 49. The resistance element is preferably grounded at its free end on a suitable contact block 50 in the bottom of the heater chamber 46 so as to form an arc when the current is on. The air may be admitted from the atmosphere to the heater chamber 46 through the opening 51, which may be fitted with an orifice block having an orifice 52 of a size suitable to the fuel used. Preferably this orifice is inclined downwardly as shown in Fig. 6 to direct the entering air against the hottest part of the arc. In very cold weather, or if for any reason the device does not start readily, liquid fuel may be squirted into the chamber 46 through the orifice 52, where it will be flashed into vapor by the arc.

A three way cock 53 is fitted in the fuelizer mixing tube for closing the opening 45 from the atmosphere and opening the passage from the heater chamber for starting the vaporizer (see Fig. 6), and vice versa under normal running conditions (see Fig. 4). This cock 53 has a handle 54 which may be connected in any suitable manner to a control handle (not shown) on the instrument board or other convenient location.

A spark plug 55 is screwed into the combustion chamber 38 to ignite the combustible mixture therein. This spark plug is connected to a jump spark coil or other source

of high tension current by means of a suitable conductor 56 whereby a stream of sparks is maintained across the gap between the points of the spark plug while the vaporizer is in operation, thereby insuring the ignition and continuous burning of the rich fuel mixture in the chamber 38.

In the form of device illustrated in Figs. 1 to 7, the burning fuel mixture is conducted through a heat transfer tube 58 arranged in the combustion chamber 38 and which has a middle flange 59 separating the latter into upper and lower spaces. The lower walls of the tube 58 are thickened and provided with a large number of small openings 60 through which the hot products of combustion of the burning fuel mixture pass into the lower space of the combustion chamber and thence through an outlet duct 61 (see Fig. 7) into the lower end of the mixing tube 16 where it mixes with cold air from the auxiliary air valve opening 18 and flows through the throat 15 past the fuel jet 14. These small openings 60 extinguish the flame of the burning fuel and prevent further combustion, the temperature of the products of combustion not being high enough for them to ignite after passing through, so no further burning takes place even after the mixture is further enriched by fuel from the jet 14.

The heat generated in the combustion chamber 38 is partly utilized in vaporizing a portion of fuel mixture in the vaporizing passages 65, which, in the embodiment of the invention shown in Figs. 1 to 7, are formed in the upper walls of the heat transfer tube 58 and which discharge into the mixing chamber 26 through an orifice 66 above the main fuel nozzle 14 (see Fig. 7). The liquid fuel is supplied to the fuel mixture for vaporizing through a jet nozzle 62 (see Fig. 4), arranged in a mixing tube 63 alongside of the fuelized mixing tube 39. The vaporizer nozzle 62 is similar to the fuelizer nozzle 40, and is fed from the same supply duct 43 and provided with needle valve adjusting means like the fuelizer nozzle. The vaporizer mixing tube 63 is closed by the cock 53 when the vaporizer is first started and is warming up, a passage 64 through this valve serving to admit atmospheric air under normal operating conditions past the nozzle 62 to the mixing tube 63 and thence to the vaporizing passages 65. A control valve 67 having an operating lever 68 is also fitted in the vaporizer mixing tube between the fuel nozzle 62 and the vaporizing passages 65 for regulating the amount of fuel mixture drawn into the vaporizer. A screw 69 working in a slot 70 in the valve 67 holds it in place while permitting freedom of movement between its two extreme operating positions. When the engine is warming up or running idle or under light load this valve may be closed, suitable control devices attached to the lever 130

68 and leading to the instrument board or other convenient place being provided for this purpose.

In the embodiment of the invention illustrated in Fig. 8, the burning mixture in the chamber 38 is drawn through the throat of the Venturi device 71 directly into the passage 72 leading to the upper end of the mixing tube 16, and is deflected past the main fuel nozzle 14 by means of the inverted outlet pipe or hood 73. The nozzle 74 of the Venturi device 71 supplies cold air from the auxiliary air valve 19 and passage 61, into which part of the cold air enters when the valve is released after starting, and flows rapidly through the throat of the Venturi device to the passage 72, where the two streams merge and any flame from the combustion chamber is damped thereby before reaching the nozzle 14. The vaporized fuel is drawn from the mixing tube 63 through the vaporizing tube 75, which leads to the chamber 76 below the combustion chamber. Thence the vaporized fuel is drawn through the passages 77 to the space 78 surrounding the throat 79, in the lower part of the mixing tube 16, where it mixes with the auxiliary air and passes directly into the upper end of the mixing tube 16 past the main nozzle 14. With this construction the control valve 67 may be kept closed entirely and satisfactory results attained by suitably adjusting the auxiliary air valve 19 and high speed valve 30 to suit the fuel being vaporized. The proportions of the nozzle 74 and throat 79 should be such as to cause a substantial volume of air to flow through each.

The operation of the device for starting an automobile engine, for example, is as follows: 40 The controls connected to the valve operating levers 24, 36 and 68 are set to close or lock the valves 19, 30 and 67 shut; and the control for lever 54 operating the three way cock 53 is set to open the passage straight through 45 from the heater chamber to the fuelizer mixing tube 39. The throttle valve 13 is opened slightly, the electric circuit through the carbon electrode 47 in the heater chamber is completed, and the motor is turned over, either by hand or by any suitable mechanical starting device. If the motor has an electrical starting device, the switch for supplying current to the carbon electrode 47 may be 50 omitted and this current be taken from the motor starting circuit. The heater current is only needed for a few seconds because of the heat of the arc.

Rotation of the motor draws air through 60 the heater chamber 46, past the fuel nozzle 40 where it picks up partly atomized fuel, and into the combustion chamber 38 where it is ignited by the continuously sparking plug 55 and partially burns. The products of combustion and unburned fuel mixture pass

through the orifices 60 in the heat transfer tube 58 in the form of device illustrated in Figs. 1 to 7, (through the Venturi device 71 in the form illustrated in Fig. 8,) and thence ultimately past the main fuel nozzle 14 where they are further enriched with atomized fuel, and into the motor. The high temperature due to the combustion of a part of the fuel mixture vaporizes the remaining part of the fuel mixture, but any tendency of the flame to lengthen out and follow the flow of gaseous materials is checked by the small orifices 60 in the tube 58 or by the walls of the nozzle 74 and Venturi device 71.

After the motor has run a sufficient length of time for the walls and passages of the combustion chamber to become well heated, the three way cock 53 is turned to normal position and the valves 19 and 30 are released to function normally. The control valve 67 may be kept closed until the vaporizer is well warmed up, and then opened or closed to suit the requirements, being closed to increase and opened to decrease the temperature of the vaporizer. A temperature producing a dull red color in the tube 58 or parts contained in the chamber 38 is satisfactory for vaporizing fuels of the gravity of kerosene. The modified form of device shown in Fig. 8 operates similarly, but attains a satisfactory vaporizing temperature sooner than the device shown in Figs. 1 to 7.

In the claims the word "throat" is used to designate a connecting passage not necessarily of less cross-sectional area than the chambers or passages that it connects.

Having described a preferred form of the invention, without restricting ourselves thereto, what we claim is as follows:

1. A vaporizer comprising a mixing tube and mixing chamber connected by a throat, a fuel nozzle in said throat, a liquid fuel supply well and duct therefrom to said nozzle, a combustion chamber discharging into said mixing tube, means for supplying fuel mixture thereto, a vaporizing tube in juxtaposition to said combustion chamber, said vaporizing tube discharging into said mixing chamber, means for supplying fuel mixture to said vaporizing tube, and means for maintaining combustion in said combustion chamber.

2. A vaporizer comprising a mixing tube and mixing chamber connected by a throat, a fuel nozzle in said throat, a liquid fuel supply well and duct therefrom to said nozzle, a combustion chamber discharging into said mixing tube, means for supplying fuel mixture thereto, an auxiliary air valve opening into said mixing tube, a vaporizing tube in juxtaposition to said combustion chamber, said vaporizing tube discharging into said mixing chamber, means for supplying fuel mixture to said vaporizing tube, and means for main-

taining combustion in said combustion chamber.

3. A vaporizer comprising a mixing tube and mixing chamber connected by a throat, a fuel nozzle in said throat, a liquid fuel supply well and duct therefrom to said nozzle, a combustion chamber discharging into said mixing tube, means for supplying fuel mixture thereto, an auxiliary air valve opening into said mixing tube, a vaporizing tube in juxtaposition to said combustion chamber, said vaporizing tube discharging into said mixing chamber, means for supplying fuel mixture to said vaporizing tube, a nozzle in said mixing chamber, a liquid fuel duct from said well to said nozzle passing contiguous to said combustion chamber, a suction operated air valve for admitting air past said nozzle to said chamber, means associated with said valve for opening said nozzle when said valve is opened by the suction, and means for maintaining combustion in said combustion chamber.

4. A vaporizer comprising a mixing tube and mixing chamber connected by a throat, a fuel nozzle in said throat, a liquid fuel supply well and duct therefrom to said nozzle, a combustion chamber discharging into said mixing tube, means for supplying fuel mixture thereto, an auxiliary air valve opening into said mixing tube, adjustable means for controlling the amount of opening of said valve, a vaporizing tube in juxtaposition to said combustion chamber, said vaporizing tube discharging into said mixing chamber, means for supplying fuel mixture to said vaporizing tube, a nozzle in said mixing chamber, a liquid fuel duct from said well to said nozzle passing contiguous to said combustion chamber, a suction operated air valve for admitting air past said nozzle to said chamber, means associated with said valve for opening said nozzle when said valve is opened by the suction, and means for maintaining combustion in said combustion chamber.

5. A vaporizer comprising a mixing tube and mixing chamber connected by a throat, a fuel nozzle in said throat, a liquid fuel supply well and duct therefrom to said nozzle, a combustion chamber discharging into said mixing tube, means for supplying fuel mixture thereto, an auxiliary air valve opening into said mixing tube, adjustable means for controlling the amount of opening of said valve, a vaporizing tube in juxtaposition to said combustion chamber, said vaporizing tube discharging into said mixing chamber, means for supplying fuel mixture to said vaporizing tube, a nozzle in said mixing chamber, a liquid fuel duct from said well to said nozzle passing contiguous to said combustion chamber, a suction operated air valve for admitting air past said nozzle to

said chamber, means associated with said valve for opening said nozzle when said valve is opened by the suction, an electric heater for increasing the temperature of said combustion chamber and mixture at starting, and means for maintaining combustion in said combustion chamber.

6. A vaporizer comprising a mixing tube and mixing chamber connected by a throat, a fuel nozzle in said throat, a liquid fuel supply well and duct therefrom to said nozzle, a combustion chamber discharging into said mixing tube, means for supplying fuel mixture thereto, an auxiliary air valve opening into said mixing tube, a vaporizing tube in juxtaposition to said combustion chamber, said vaporizing tube discharging into said mixing chamber, means for supplying fuel mixture to said vaporizing tube, a nozzle in said mixing chamber, a liquid fuel duct from said well to said nozzle passing contiguous to said combustion chamber, an electric heater for increasing the temperature of said combustion chamber and mixture at starting, and means for maintaining combustion in said combustion chamber.

7. A vaporizer comprising a mixing tube and mixing chamber connected by a throat, a fuel nozzle in said throat, a liquid fuel supply well and duct therefrom to said nozzle, a combustion chamber discharging into said mixing tube, means for supplying fuel mixture thereto, an auxiliary air valve opening into said mixing tube, a vaporizing tube in juxtaposition to said combustion chamber, said vaporizing tube discharging into said mixing chamber, means for supplying fuel mixture to said vaporizing tube, a nozzle in said mixing chamber, a liquid fuel duct from said well to said nozzle passing contiguous to said combustion chamber, a suction operated air valve for admitting air past said nozzle to said chamber, an electric heater for increasing the temperature of said combustion chamber and mixture at starting, and means for maintaining combustion in said combustion chamber.

8. A vaporizer comprising a mixing tube and mixing chamber connected by a throat, a fuel nozzle in said throat, a liquid fuel supply well and duct therefrom to said nozzle, a combustion chamber discharging into said mixing tube, means for supplying fuel mixture thereto, a vaporizing tube in juxtaposition to said combustion chamber, said vaporizing tube discharging into said mixing chamber, means for supplying fuel mixture to said vaporizing tube, a nozzle in said mixing chamber, a liquid fuel duct from said well to said nozzle passing contiguous to said combustion chamber, a suction operated air valve for admitting air past said nozzle to said chamber, means associated with said valve for opening said nozzle when said valve is opened by the suction, an electric heater

for increasing the temperature of said combustion chamber and mixture at starting, and means for maintaining combustion in said combustion chamber.

9. A vaporizer comprising a mixing chamber, a main fuel nozzle, a heating chamber, an electric resistance element in association with said heating chamber for starting operation of the vaporizer, a walled passage 10 through said heating chamber discharging into said mixing chamber, a fuel nozzle in said passage, valve means for admitting air to said passage, and a suction operated air valve for admitting air to said mixing 15 chamber.

10. A vaporizer having a main fuel supply nozzle and two auxiliary fuel supply nozzles, air supply means for said auxiliary nozzles, a combustion chamber into which the mixture 20 from one of said auxiliary supply nozzles discharges and means for igniting said mixture therein, a vaporizer passage in proximity to said combustion chamber into which the mixture from said other auxiliary supply 25 nozzle discharges, and means for controlling the air supply means for said other auxiliary supply nozzle to alter the relative quantities of fuel supplied by said auxiliary nozzles to said combustion chamber and vaporizing 30 passage, respectively.

11. A vaporizer having a main fuel supply nozzle and two auxiliary fuel supply nozzles, air supply means for said auxiliary nozzles, a combustion chamber into which the mixture 35 from one of said auxiliary supply nozzles discharges and means for igniting said mixture therein, a vaporizer passage in proximity to said combustion chamber into which the mixture from said other auxiliary supply nozzle 40 discharges, and means for controlling the air supply means for said other auxiliary supply nozzle to alter the relative quantities of fuel supplied by said auxiliary nozzles to said combustion chamber and vaporizing 45 passage, respectively, in combination with an additional air supply means for diluting the products of combustion from said combustion chamber prior to mingling them with the mixture from said vaporizer passage.

50 12. A vaporizer having a main fuel supply nozzle and two auxiliary fuel supply nozzles, air supply means for said auxiliary nozzles, a combustion chamber into which the mixture 55 from one of said auxiliary supply nozzles discharges, an electric heating device for initially heating the air supply for said auxiliary nozzle, a vaporizer passage in proximity to said combustion chamber into which the mixture from said other auxiliary supply nozzle discharges, and means for controlling the air supply means for said auxiliary supply nozzle to alter the relative quantities of fuel supplied by said auxiliary nozzles to said combustion chamber and vaporizing 60 passage, respectively.

13. A vaporizer having a main fuel supply nozzle and two auxiliary fuel supply nozzles, air supply means for said auxiliary nozzles, a combustion chamber into which the mixture from one of said auxiliary supply nozzles discharges, an electric heating device for initially heating the air supply for said auxiliary nozzle, said heating device comprising a chamber having a restricted air supply opening, and valve means for closing the passage from said chamber to said nozzle when said heating device is not required, in combination with a vaporizer passage in proximity to said combustion chamber into which the mixture from said other auxiliary supply nozzle discharges, and means for controlling the air supply means for said auxiliary nozzle to alter the relative quantities of fuel supplied by said auxiliary nozzles to said combustion chamber and vaporizing passage, respectively. 70 75 80 85

14. A vaporizer having a main fuel supply nozzle and two auxiliary fuel supply nozzles, air supply means for said auxiliary nozzles, a combustion chamber into which the mixture from one of said auxiliary supply nozzles discharges, an electric heating device for initially heating the air supply for said auxiliary nozzle, said heating device comprising a chamber having a restricted air supply opening, and valve means for closing the passage from said chamber to said nozzle when said heating device is not required, in combination with a vaporizer passage in proximity to said combustion chamber into which the mixture from said other auxiliary supply nozzle discharges, and means for controlling the air supply means for said auxiliary nozzle to alter the relative quantities of fuel supplied by said auxiliary nozzles to said combustion chamber and vaporizing passage, respectively. 90 95 100 105 110

15. A vaporizer having a main fuel supply nozzle and two auxiliary fuel supply nozzles, air supply means for said auxiliary nozzles, a combustion chamber into which the mixture from one of said auxiliary supply nozzles discharges, an electric heating device for initially heating the air supply from said auxiliary nozzle, and a double valve having means for simultaneously closing said air supply and opening the air supply to the other auxiliary fuel supply nozzle, a vaporizer passage in proximity to said combustion chamber into which the mixture from said other auxiliary supply nozzle discharges, and means for controlling the air supply means for said auxiliary supply nozzle to alter the relative quantities of fuel supplied by said auxiliary nozzles to said combustion chamber and vaporizing passage, respectively. 115 120 125 130

16. A vaporizer comprising two mixing chambers connected by a throat, a main fuel supply nozzle in said throat, a combustion chamber discharging into one of said mixing chambers, means for supplying fuel mixture to said combustion chamber, an igniting device therefor, a vaporizing chamber adjacent to said combustion chamber and discharging into the other of said mixing chambers, and means for supplying fuel to said vaporizing chamber.

17. A vaporizer comprising two mixing chambers connected by a throat, a main fuel supply nozzle in said throat, a combustion chamber discharging into one of said mixing chambers, means for supplying fuel mixture to said combustion chamber, an igniting device therefor, a vaporizing chamber adjacent to said combustion chamber and discharging into the other of said mixing chambers, means for supplying fuel and air in suitable proportions to said vaporizing chamber, and a normally closed suction operated air valve for admitting air to said mixing chamber.

18. A vaporizer for internal combustion engines comprising a mixing chamber having a main fuel nozzle, a valve controlled air supply passage leading thereto, a combustion chamber having fuel and air supply means and ignition means therefor, and a vaporizing passage leading to said mixing chamber and provided with fuel and air supply means, said vaporizing passage having a chamber portion adjacent to said combustion chamber for receiving and vaporizing a quantity of air and fuel ready for supplying said mixing chamber as needed to meet the varying demand of the engine.

19. A vaporizer for internal combustion engines comprising in combination a mixing chamber having a fuel nozzle discharging therein, a valve controlled air supply passage leading thereto, a combustion burner chamber, means associated therewith including a source of heat independent of the engine for supplying a preheated combustible fuel mixture thereto for starting the engine, a fuel supply conduit leading to said fuel nozzle and having a portion arranged to absorb heat from the combustion chamber and means to control the supply of fuel to said conduit.

20. A heavy fuel vaporizer for internal combustion engines comprising, in combination, a main mixing chamber, a main air inlet conduit discharging into the mixing chamber and having a contracted throat adjacent thereto, a fuel nozzle in said throat, cooperating high speed fuel and air inlets also discharging into the mixing chamber, and a combustion burner arranged to vaporize the fuel in the mixing chamber and to preheat the high speed fuel.

21. A heavy fuel vaporizer for internal combustion engines comprising, in combina-

tion, a main mixing chamber, a main air inlet conduit discharging into the mixing chamber and having a contracted throat adjacent thereto, a fuel nozzle in said throat, cooperating high speed fuel and air inlets also discharging into the mixing chamber, and a combustion burner also connected to discharge products of combustion into the main air inlet conduit and arranged to preheat the high speed fuel.

22. A vaporizer for internal combustion engines comprising in combination a mixing chamber, a main carburetor discharging into the mixing chamber and having an air inlet, a secondary carburetor arranged to supply a controlled mixture of fuel and air to the mixing chamber, a combustion burner for preheating the secondary fuel mixture, said burner being connected to discharge products of combustion into the air inlet passage of the main carburetor.

23. A vaporizer for internal combustion engines comprising, in combination, a mixing chamber and means for supplying a controlled mixture of fuel and air thereto, supplemental means for supplying a controlled mixture of fuel and air to said mixing chamber, and means for preheating said last named mixture after it is formed and prior to admitting it to said mixing chamber, said preheating means including an electric heating device.

24. A vaporizer for internal combustion engines comprising in combination, a mixing chamber and means for controlling the supply of fuel and air thereto, supplemental means for supplying a controlled mixture of fuel and air to said mixing chamber, a preheating chamber for said supplemental mixture supplying means, a combustion burner for heating said preheating chamber, mixture supplying means for said combustion burner, and electric heating means for starting operation of said combustion burner.

25. A vaporizer comprising a main mixing chamber containing a liquid fuel nozzle, a gasifier chamber discharging fuel combustion products into the main mixing chamber in proximity to said nozzle, a vaporizer nozzle discharging into the main mixing chamber, and a vaporizer chamber for supplying vaporized fuel mixture to said nozzle heated by conduction from the gasifier chamber, and means for supplying air and fuel to said gasifier chamber and vaporizer chamber independently of the supply to said main mixing chamber.

26. A vaporizer comprising a main mixing chamber containing a liquid fuel nozzle, a gasifier chamber discharging fuel combustion products into the main mixing chamber in proximity to said nozzle, a vaporizer nozzle discharging into the main mixing chamber, means for supplying additional air to said

gasifier chamber and vaporizer nozzle, and a vaporizer chamber for supplying vaporized fuel mixture to said nozzle heated by conduction from the gasifier chamber, and means for supplying air and fuel to said gasifier chamber and vaporizer chamber independently of the supply to said main mixing chamber.

27. A vaporizer comprising a main mixing chamber containing a liquid fuel nozzle, a gasifier chamber discharging fuel combustion products into the main mixing chamber in proximity to said nozzle, a vaporizer nozzle discharging into the main mixing chamber, and a vaporizer chamber for supplying vaporized fuel mixture to said nozzle heated by conduction from the gasifier chamber, and means for supplying air and fuel to said gasifier chamber and vaporizer chamber independently of the supply to said main mixing chamber, in combination with an electric starting device for initially heating the fuel supplied to said gasifier chamber.

28. A heavy fuel vaporizer having a combustion chamber and a liquid fuel supply, means for supplying a rich mixture of fuel and air to said combustion chamber, means for igniting said mixture and partly burning and vaporizing the fuel content thereof, a main air duct and communicating passage leading to a mixing chamber, said combustion chamber discharging into said passage through flame extinguishing means, a valve controlling the flow of air through said duct, fuel vaporizing means associated with said combustion chamber to be heated thereby and discharging into said mixing chamber, and valves for regulating the supply of fuel to said combustion chamber and to said mixing chamber from said fuel supply.

40 29. A heavy fuel vaporizer having a combustion chamber and a liquid fuel supply, means for supplying a rich mixture of fuel and air to said combustion chamber, means for igniting said mixture and partly burning and vaporizing the fuel content thereof, a main air duct and communicating passage leading to a mixing chamber, said combustion chamber discharging into said passage through flame extinguishing means, a valve controlling the flow of air through said duct, fuel vaporizing means associated with said combustion chamber to be heated thereby and discharging into said mixing chamber, valves for regulating the supply of fuel to said combustion chamber and to said mixing chamber from said fuel supply, and means for controlling said main air duct valve and said fuel supply valves for producing a rich mixture composed largely of combustion products in said combustion and mixing chambers for starting purposes.

30. A heavy fuel vaporizer for internal combustion engines comprising, in combination, a combustion burner having an igniter therein,

means initially to supply a readily combustible fuel mixture to the burner for starting purposes, means to supply aspirated heavy fuel to the burner after it is initially heated, the amount of air supplied to the burner being inadequate to support complete combustion of the fuel mixture, means for extinguishing the flame in said burner before it reaches the engine intake passage, a secondary mixing chamber into which the partial products of combustion are discharged, an inlet opening controlled by the engine suction also discharging into said secondary mixing chamber, and a fuel heating conduit associated in heat exchanging relation with said combustion chamber and connected to discharge additional fuel into said secondary mixing chamber.

31. Apparatus for vaporizing heavy fuels for internal combustion engines which comprises a combustion burner, and an intake passage leading to the engine, means for initially supplying a readily combustible over rich mixture of fuel and air to the said combustion burner for starting purposes, means for igniting the mixture and discharging the partial products of combustion into the intake passage, means for admitting an aspirated rich mixture of the heavy fuel in lieu of the initial supply to the burner chamber after it becomes heated, means for controlling said aspirated mixture operated by the engine suction, heating means associated with said combustion burner for heating to vaporizing temperature under reduced pressure an additional or auxiliary supply of the heavy fuel, and means operated by the engine suction for admitting into said intake passage a controlled supply of the preheated or vaporized fuel and air in mixing relation with the partial combustion products, said last named means being adjusted to operate when the engine creates heavy suction in the intake passage.

32. Apparatus for vaporizing heavy fuels for internal combustion engines which comprises a combustion burner and intake passage leading to the engine, means for initially supplying a readily combustible over rich mixture of fuel and air to said combustion burner for starting purposes, means for igniting the mixture and discharging the partial products of combustion into the intake passage, means for admitting an aspirated rich mixture of the heavy fuel in lieu of the initial supply to the burner chamber after it becomes heated, means for controlling said aspirated mixture operated by the engine suction, means for supplying supplemental air and preheating it by the combustion burner, means for supplying supplemental heavy fuel and preheating it also by the combustion burner, and means for intermingling the partial combustion products with

the supplemental fuel and air in the intake passage before they reach the main intake manifold.

In testimony whereof, we have signed our names to this specification.

ROBERT F. LONABERGER.
CHARLES F. SANDS.
